UNITED STATES PATENT OFFICE.

WILLIAM S. ROBINSON, OF CHICAGO, ILLINOIS, ASSIGNOR TO ARMSTRONG BROS. TOOL CO., OF CHICAGO, ILLINOIS, A CORPORATION OF ILLINOIS.

PLANER-TOOL HOLDER.

1,252,031.

Specification of Letters Patent.

Patented Jan. 1, 1918.

Application filed December 26, 1916. Serial No. 138,735.

To all whom it may concern:

Be it known that I, WILLIAM S. ROBINSON, a citizen of the United States, residing at Chicago, in the county of Cook and State of Illinois, have invented certain new and useful Improvements in Planer-Tool Holders, of which the following is a specification.

This invention relates to planer tools and its object is to provide an improved tool holder wherein short length cutters may be adjustably secured.

A further object of this invention is to provide an offset supporting shank for the cutting-tool holder whereby the point of 15 support of the cutting tool will lie approximately in the axis of the supporting shank.

Figure 1 of the drawings is a side elevational view of a supporting shank, the cutting-tool holder, and a cutting tool, a portion of the shank being broken away. Fig. 2 is a horizontal section taken on line 2—2 of Fig. 1. Fig. 3 is a front elevational view of the holder. Fig. 4 is a sectional view taken on line 4—4 of Fig. 1. Fig. 5 is a 25 perspective view of an offset supporting shank, a portion thereof being broken away. Fig. 6 is a side elevational view of the offset supporting shank shown in Fig. 5 to which the tool holder has been attached.

In the accompanying drawings, 1 is a supporting bar or shank of rectangular cross-section which is adapted to be suitably secured to the tool carriage of a planer or similar machine. A preferably circular base member 2 is slidable upon the shank 1 and is rigidly secured thereto by a split socket or clamp consisting of two opposite side walls 3 and an end wall 3^a formed integral with the base member, said jaws being arranged 35 to be drawn together by a clamping screw 4 extending through two ears 3^b. One of said ears is integral with one end of one of the side walls 3, the other ear being integral with one end of the end wall 3^a. As indicated in Fig. 2, the socket or clamp is split 45 at one of its corners; thus when the screw 4 is tightened, all of the walls of the clamp are drawn into tight contact with the shank 1.

Rotatably and adjustably supported upon 50 the base member is a preferably circular tool holder or head 5. The holder comprises a clapper box structure having a transversely slotted portion 6 wherein is pivotally supported a clapper tongue 7 carrying a cutting

tool 8. Any suitable means, as the pin 9, 55 may pivotally secure the tongue in the slotted portion 6. The clapper tongue is preferably arcuately rounded or beveled opposite the pivotal support as shown at 10 in Fig. 1. The cutting tool 8 is adjustably secured in a tool slot 11 by any suitable means, that herein shown being a set screw 12.

The means for normally holding the clapper tongue in the position shown in Fig. 1 comprises a leaf-spring 13 secured to the clapper box 5 by one or more screws 14 and a pin 15 carried by the clapper tongue 7. Upon the non-cutting or return stroke, the spring 13 yields to allow the tongue 7 to turn upon its pivot as the tool drags over the work. Upon the forward or cutting stroke the force applied by the spring 13 and later the resistance of the material to be cut and the working force applied by the machine will cause the tongue 7 to abut against the 75 bottom wall 16 of the slotted portion 6 for support.

The means for adjustably and rotatably securing the clapper box structure 5 to the base 2 is as follows: A central pivot member 80 17 axially carried by the base portion of the clapper box is rotatably seated in a central opening 18 in the base member 2. In the base member and concentric with the central opening is an annular T-slot 19 opening 85 upon the face adjacent the clapper box. Through a suitably shaped hole 20 is insertible a T-bolt 21 or preferably two T-bolts each having a flanged head 22 adapted to underlie the walls 23 of the T-slot 19. The 90 heads 22 of the bolts are of any desired shape to slidably and non-rotatably secure each bolt in the T-slot. The base portion of the clapper box 5 has the bolt holes 24 through which the bolts 21 are adapted to be passed. 95 Washers 25 and nuts 26 are mounted on the outer ends of the bolts. The clapper box structure 5 is in this manner rigidly and adjustably secured to the base member 2.

In Fig. 5, I have shown a supporting bar 100 or shank 27 having an intermediate transverse portion 28 and an offset portion 29. When the circular tool holder 5 and the base member 2 are secured upon the offset portion, the point of support of the cutting tool 105 will lie approximately in the axis of the bar. If desired, the intermediate portion of the bar may be cut away to provide an arcuate

surface 30 as indicated in Fig. 5 to accommodate the upper portion of the base 2 and clapper box 6.

From the foregoing it will be seen that the base member 2 may be securely clamped to the supporting bar at any point, thereby roughly adjusting the tool. The clapper box structure may be rotatably adjusted upon the base and then rigidly secured thereto, thereby adjusting the tool to the desired angle. The cutting tool is thereupon adjusted in the tool slot of the clapper tongue and rigidly secured by the set screws thereon for taking the desired depth of cut.

It is apparent that, with the foregoing described improved tool holder, long-shanked planer tools and special side tools are unnecessary and short-length cutters may be employed more efficiently than in prior structures.

While I have described in considerable detail the preferred embodiment of my invention, I would have it understood that I will be limited only by the appended claims.

I claim as my invention:

1. A tool-holder having, in combination, a supporting shank; a base member slidable thereon and adapted to be rigidly secured thereto, said base member having a central opening, an annular T-slot concentric with said opening, and an insert hole communicating with said T-slot; securing means comprising a pair of clamping jaws rigid with said base member and a clamping screw; a clapper box structure comprising a base portion having a transverse slot therein and a hole extending through the base portion and communicating with said T-slot, a central pivot rigid with said base portion and seated in said central opening, and a clapper tongue tool-holder pivotally mounted in said transverse slot comprising a body portion having a tool slot, a rounded end portion opposite said pivotal mounting, and means for securing a tool in said tool slot; and means for rigidly securing said clapper box structure to said base member comprising a T-bolt insertible through said insert hole and having a flanged head adapted to underlie the walls of said T-slot and a body portion insertible through said communicat-

ing hole and means for securing said bolt in said communicating hole.

2. A tool-holder having, in combination, a supporting shank, a base member slidable thereon and adapted to be rigidly secured thereto, securing means comprising clamping jaws rigid with said member and a clamping screw, and a clapper box structure comprising a base portion rotatably adjustable upon and rigidly secured to said base member and having a slot therein and a clapper tongue tool-holder pivotally mounted in said slot, said clapper tongue having an arcuately rounded end portion and a tool slot.

3. A tool-holder having, in combination, a supporting shank having an offset portion, a base member slidable thereon and adapted to be rigidly secured thereto, and a clapper box tool-holder rotatably adjustable upon and rigidly secured to said base member, the point of support of the tool lying approximately in the axis of the supporting shank.

4. A tool-holder having, in combination, a supporting shank having an intermediate transverse portion having an arcuate surface and an offset portion, a circular base member slidable thereon and adapted to be rigidly secured thereto, and a circular clapper box tool-holder rotatably adjustable upon and rigidly secured to said base member, the point of support of the tool lying approximately in the axis of the supporting shank, the circular base member abutting against said arcuate surface.

5. A tool-holder having, in combination, a rectangular shank, a rectangular socket member having inclosing walls adapted to surround the shank, said socket member being split at one corner, ears on the socket member at opposite sides of the split, and a clamping screw for drawing the ears together and thus drawing all of the walls of the socket member into engagement with the shank to secure the socket-member in adjusted position.

In testimony whereof, I have hereunto set my hand.

WILLIAM S. ROBINSON.
